John Hyslop

UNITED STATES PATENT OFFICE.

JOHN HYSLOP, OF NEW YORK, N. Y.

IMPROVED VENTILATOR.

Specification forming part of Letters Patent No. 44,196, dated September 13, 1864.

To all whom it may concern:

Be it known that I, JOHN HYSLOP, of the city, county, and State of New York, have invented a new and Improved Ventilator; and I do hereby declare that the following is a full, clear, and exact description thereof, which will enable others skilled in the art to make and use the same, reference being had to the accompanying drawings, making a part of this specification, in which—

Figure 1 is a vertical section of my invention, taken in the line xx , Fig. 2; Fig. 2, an inverted plan of the same; Fig. 3, a diagram showing the application of the invention to the lower stories of a building.

Similar letters of reference indicate like parts.

This invention consists in constructing the ventilator with louvers at its sides, and with partitions, one or more, and also with bottom louvers or an equivalent device, all arranged in such a manner that due provision is made for the ingress and egress of the air and a current allowed to pass through the compartments of a building, the invention being applicable to buildings of any number of stories.

A represents a case or box, which is divided into two compartments, a a' , by a vertical central partition, B, and is provided with a roof or top, b, of any suitable form or construction. At two opposite sides of the case or box A there are placed louvers C, any suitable number at each side. These louvers are of double inclined form, as shown in Fig. 1, the outer parts, c, inclining downward and outward from their inner to their lower edges, and the inner parts, d, inclining downward and inward from the upper to their lower edges, the upper ends of the inner parts, d, slightly overlapping the upper ends of the outer parts, c, in order to prevent the admission of rain and snow by being driven over the top of the outer part. At the bottom of the case or box A, under each compartment, there are placed horizontal louvers D, those of one compartment being inclined in a reverse direction to those of the other, as shown

in Fig. 1. In each compartment there is a damper, E, having cords or chains e attached to them, which pass through the partition-plate B, and are connected to a common cord or chain, e', by which the dampers may be opened and closed. The air passes through the louvers C at the windward side of the case or box A, and is deflected downward by the inner parts, d, and passes through the bottom louvers, D, of compartment a into the building, the ascending current passing up through the louvers D of the other compartment, a' , and out between the louvers C of said compartment, the inner parts, d, deflecting the ascending current outward, as indicated by the arrows. By this arrangement the compartment has a current of air passing through it, the descending current being kept separate or apart from the ascending one. The louvers may, when several compartments in a building on different floors are to be ventilated, be placed in the side walls, as shown at f in Fig. 3; the spaces between the beams or flooring-timbers serving as draft-passages or vent-ducts, and in cases where the side walls are not exposed the air may be conducted down and allowed to pass out through pipes g, provided at their upper ends with the louvers C. The louvers D at the bottom of the case or box A may be dispensed with, and a board or deflector used instead.

Having thus described my invention, I claim as new and desire to secure by Letters Patent—

1. A ventilator divided by a partition or diaphragm, in combination with side louvers, of any desired form, and with or without the bottom louvers, substantially as described.
2. A ventilator divided into two or more compartments, in combination with the side louvers, C, constructed as described, and either with or without the bottom louvers, D, as set forth.

JOHN HYSLOP.
